(57) **CLAIM**

The ornamental design for a packaging container, as shown and described.

DESCRIPTION

FIG. 1 is a front elevational perspective view of an embodiment of a packaging container of my design;
FIG. 2 is a rear elevational perspective view of thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof;
FIG. 8 is a bottom plan view thereof;
FIG. 9 is a sectional view taken along plane 9-9 of FIG. 3;
FIG. 10 is a front elevational perspective view of a second embodiment of a packaging container of my design;
FIG. 11 is a rear elevational perspective view of thereof;
FIG. 12 is a front elevational view thereof;
FIG. 13 is a rear elevational view thereof;
FIG. 14 is a right side elevational view thereof, the left side elevational view thereof being a mirror image and symmetrical to the right side elevational view thereof and being omitted;
FIG. 15 is a top plan view thereof;
FIG. 16 is a bottom plan view thereof; and,
FIG. 17 is a sectional view taken along plane 17-17 of FIG. 12.
